ELECTRON GUN MOUNTING

Stanley V. Forgue, Cranbury, N. J., assignor to
 Radio Corporation of America, a corporation
 of Delaware

Application January 28, 1946, Serial No. 643,925

7 Claims. (Cl. 250—162)

1

This invention relates to mounts for the cathode, control electrode and first anode of a television cathode ray transmitting tube, such as disclosed, for example, in the application of Paul K. Weimer, filed September 16, 1944, Serial No. 554,494, now Patent #2,433,941, although it is not limited thereto.

An object of the invention is to mount the elements of the gun rigidly together so as to be essentially free from microphonics.

Another object of the invention is to construct the mounting of the gun elements so that they may be readily assembled in accurate spaced relation to each other.

Other objects of the invention will appear in the following specification, reference being had to the drawings, in which:

Fig. 1 is a longitudinal section through the gun and the mounts therefor.

Fig. 2 is an elevation of the anode cylinder of the gun.

Fig. 3 is an end view of the anode cylinder, as viewed from the right of Fig. 2.

Fig. 4 is an elevation of the dynode end of the anode before being inserted in the cylinder of Fig. 2.

Fig. 5 is a view of the dynode end of the anode, as viewed from the right in Fig. 4.

Fig. 6 is an elevation of the grid cylinder before the end cap is inserted therein.

Fig. 7 is an end view of the grid cylinder of Fig. 6.

Fig. 8 is a sectional view of the cathode of the gun.

Fig. 9 is an end view of the cathode, as viewed from the right in Fig. 8.

Fig. 10 is a plan view of the gun mount.

Fig. 11 is a sectional elevation, taken on the line 11—11 of Fig. 10.

Fig. 12 is a view of the two clamps in separated position which grip the heater element, shown in Fig. 1.

Fig. 13 is a plan view of the clamps of Fig. 12.

Fig. 14 is a modification.

Referring to Fig. 2, the anode has a cylindrical portion 1 with a flanged end 2. The cylindrical portion 1 has a plurality of openings 3, four in number, as indicated in this figure. These openings are used to increase the resistance of the cylinder so that when it is subjected to high frequency heating, the proper temperature may be obtained for degassing without unduly heating the mica used in various parts of the mount, as later referred to. These holes also aid in pump-

2

ing gas out of the gun and in reducing heat conduction towards the base of the gun.

The anode has end 4 to which is welded a cup 5 (see also Fig. 5) which in the final operation of the gun assembly is inserted inside of the cylinder 1 and the two parts are welded together, as appears in Fig. 1. The anode end 4 has a thin sheet 6 of silver-magnesium alloy clamped in position thereover, as appears in Fig. 1. This thin sheet of alloy constitutes the first electrode or dynode of the multiplier unit, as particularly described in the application of said Paul K. Weimer.

The grid or control electrode consists of a cylinder 7, as shown in Fig. 6. This is somewhat smaller than the anode cylinder 1 of Fig. 2, so as to fit in spaced position therein. This cylinder also has a flanged end 8 and from the flanged end is stamped or punched a connector 9, to which may be soldered the grid conductor (not shown) entering the stem of the tube. When this grid connector is punched from the tube, it, of course, leaves a slot 10 therein (Fig. 7). The grid cylinder 7 also has a plurality of holes 11, say four, for increasing the resistance for high frequency heating in the degassing operation, for ease of pumping gas out of the gun and for reducing heat conduction. A cap 12, not shown in Fig. 6 but shown in Fig. 1, is inserted inside the grid cylinder 7 and is welded thereto. The grid cylinder and cap may both be made of non-magnetic stainless steel tubing. The grid cap 12 has an aperture 13 of the order of forty mils, although this may be varied considerably in either direction depending upon the operating characteristics desired of a given gun. There is an aperture 14 of about forty mils (not critical) in the dynode end parts 4 and 5 of the first anode, while the first dynode surface 6 of silver-magnesium alloy 40 has a small beam aperture of from a fraction of a mil to several mils again depending upon the operating characteristics desired.

The cathode in Figs. 8 and 9 consists of a main cylinder 15 having an integral flange 16. The cylinder 15 may have a plurality of openings 17, eight being indicated in the drawing, to increase the resistance and high frequency heating in the degassing operation for ease of pumping gas out of the gun and for reducing heat conduction. 50 The cathode end is of standard construction, consisting of a cylinder 18 in which the cathode cylinder 15 fits and to which it is welded. Cylinder 18 has an inturned flange 19. A stub cylinder 20 is positioned in the cylindrical opening 55 of the flange 19 and has an out-turned flange 21.

A cap 22 has a flange 23 fitting against the flange 21. Flanges 19, 21 and 23 are fastened together, preferably by welding. The end 24 may have the usual thermoactive oxide coating and an insulated heater coil 25 (Fig. 1) is mounted inside the cylinders 18, 20 and cap 22. This heater coil has the two resistance wires 26, 27 reversely wound, as is usual in such heaters.

The gun mount 28 consists of a double drum or cup having a disc or base 29 stamped to have a circular flange or rim 30 with a flat disc 31, from which depends the circular rim 32, as shown in Figs. 10 and 11. The disc 31 of this mount is punched at 33 and 34 so as to have depending lugs 35, 36 extending therefrom. Cups 37, 38 are positioned on opposite sides of the disc end 29 with their bases 39, 40 in contact with the base 29. These three bases are then welded together. The three parts have openings 41, 42 merging together for passage of the cathode cylinder heater insulator, later referred to, and the grid wire 9, respectively.

The various elements of the gun may be assembled by several possible methods, one of which is as follows:

One or more mica washers, shown as a single insulator 43, are placed over the cathode cylinder 15 and against the flange 16. A flanged metal washer 44 is slipped over the cylinder 15 and the mica is pressed tightly against 16. The washer then is welded to the cylinder 15 to hold the parts in place. A mica insulator washer 45 is then placed on top of mica insulator 43 and the cathode assembly is inserted in the gun mount 28 with the insulator 45 resting against the base 39 of cup 37. A metal washer 48 is placed against insulator 43 in cup 37 and, with a suitable assembly jig and press, the rim of cup 37 is turned over at 50. The cylinder 18 of the standard cathode assembly is next slipped over the end of cathode cylinder 15 and, after being positioned by a suitable jig to give correct cathode-grid spacing, it is welded into place on the cathode cylinder. Insulator 46 is next placed against the base 40 in cup 38 and the grid cylinder assembly is placed with the flange 8 against the insulator 46. The insulators have small holes through which the grid connector 9 may pass when this assembly is made. Another insulator 47 is placed in cup 38 against flange 8 of the grid cylinder. The anode cylinder is then placed in position with the flange 2 in cup 38 resting against insulator 47. The rim of cup 38 is then turned over at 49 by means of the assembly jig previously mentioned. The assembly jig incorporates suitable mandrels to produce the correct coaxial alignment of the several cylinders during the assembly operation.

The heater wires 26, 27 are welded to conductors 51, 52 and ceramic insulator 53 is placed over the rods. Heater straps 54, 55 (Figs. 12 and 13) are then welded in proper position around insulator 53. The heater assembly is then placed inside the cathode cylinder 15 and the ends of the heater strap 55 are welded to lugs 35, 36 of the gun mount 28. The parts are now all firmly clamped in position in the gun mount and cannot move in relation to each other, no matter how roughly handled.

The cathode conductor 60 is welded to the flange 16 and the grid conductor to lug or connector 9. The anode conductor, not shown, may be connected to the rim 32 of the mount 28, as the flange 2 is clamped in direct contact with the mount at the turned-over edge 49. The flanges 8 and 16 of the grid and cathode cylinders have

less diameter than the cups 37 and 38 and hence are spaced and insulated from the mount.

If it is desired to surround the gun with other elements, such as the multiplier units and associated parts, as disclosed in my application, filed February 7, 1946, Serial No. 646,075, these are slipped over the gun in proper position and the cup 5 of the anode end assembly is slipped into the anode cylinder 1 and welded thereto, thus completing the assembly of the gun.

U-shaped straps 56, either singly or in pairs, are welded to the outside surface of drum rim 32 and the ends are bent around hollow ceramic rods 57 and then welded together. There may be as many of these rods as desired, but four spaced 90° apart are sufficient. Metal rods 58 extend through the ceramic insulators and are welded to supports 59, which are sealed in the tube stem (not shown) when the complete unit is assembled in the glass envelope.

In the modification of Fig. 14 the heater strap 61 is made somewhat longer than strap 55 of Fig. 13 and the ends are turned angularly to fit against the rim 32 of the mount, to which they are welded. The other parts would be similar to those shown in Fig. 1 and are not illustrated in Fig. 14.

The ceramic rods 57 may be used to support the multiplier elements around the gun, but these units are not illustrated herein, as this is the subject of my said copending application.

I claim:

1. In cathode ray tubes, a metal cathode cylinder having a flange at one end, an insulation washer fitting around the cathode cylinder, a metal washer in contact with the outside of said cylinder clamping the insulation washer against said flange, a metal cup having a central opening in its base, an insulation washer engaging the inside of the base of said cup, said cathode cylinder extending through said central opening with the first-mentioned washer bearing against the second-mentioned washer, and a metal washer bearing against the first-mentioned washer, the outside wall of said cup being turned over to clamp all said washers in said cup.

2. In cathode ray tubes, a metal cathode cylinder having a flange at one end, an insulation washer fitting around the cathode cylinder, a metal washer having a circular flange around its opening in contact with said cylinder, said circular flange being welded to the cylinder with the insulation washer clamped thereby against the cathode cylinder flange, a metal cup having a central opening in its base, an insulation washer engaging the inside of the base of said cup, said cathode cylinder extending through said central opening with the first-mentioned washer bearing against the second-mentioned washer, and a metal washer bearing against the first-mentioned washer, the outside wall of said cup being turned over to clamp all said washers in said cup.

3. In cathode ray tubes, a metal cup having a central opening, a cathode cylinder extending through said opening and having a flange, means for clamping the flange against the base of said cup, a heater element inside said cathode and means for supporting said heater element on the inside wall of said cup.

4. In cathode ray tubes, a metal cup having a central opening in its base, an insulation washer on the base of said cup, a metal grid cylinder having an end flange on said insulation washer, an insulation washer on the flange of said grid cylinder, and an anode cylinder having an end

flange on the last-mentioned insulation washer, the wall of said cup being turned over at the top to clamp said flanges and washers against the base thereof.

5. In cathode ray tubes, a main cup, a pair of smaller cups, said cups having central openings, the bases of the auxiliary cups being secured to the opposite sides of the base of the main cup with the said openings in alignment, a cathode cylinder having a flange at one end, a larger grid cylinder having a flange at one end, said flanges being of lesser diameter than the inside diameter of said auxiliary cups, a still larger anode cylinder having a flange at one end, said cathode cylinder extending through said central openings with its flange in the inner auxiliary cup, said grid cylinder being mounted around said cathode cylinder with its flange in the outer auxiliary cup, said anode cylinder being mounted around said grid cylinder with its flange inside said outer cup, insulation discs in said cups with central openings fitting around said cylinders and resting against sides of the cathode and grid flanges and against the inner side of the anode flange, the walls of said auxiliary cups being turned over and compressing the flanges and insulation washers in said cups.

6. In cathode ray tubes, a main cup, a pair of cups, said cups having central openings, the bases of the auxiliary cups being secured to the opposite sides of the base of the main cup with the said openings in alignment, a cathode cylinder extending through said central openings,

grid and anode cylinders extending through one of said openings, all said cylinders having flanges clamped in said auxiliary cups, a plurality of supporting rods extending axially of said cups and spaced apart around the perimeter of the main cup, and means for securing the main cup to said rods.

7. In cathode ray tubes, a main cup, a pair of smaller cups, said cups having central openings, the bases of the auxiliary cups being secured to the opposite sides of the base of the main cup with said openings in alignment, a cathode cylinder extending through said central openings, grid and anode cylinders extending through one of said openings, all said cylinders having flanges clamped in said auxiliary cups, a plurality of supporting rods extending axially of said cups and spaced apart around the perimeter of the main cup, means for securing the main cup to said rods, 20 a heater element inside said cathode cylinder and means for securing said heater element to the inside wall of the main cup.

STANLEY V. FORGUE.
